UNITED STATES PATENT OFFICE.

ERNEST A. HAVENS, OF PEORIA, ILLINOIS, ASSIGNOR TO MARK D. BATCHELDER, OF PEORIA, ILLINOIS.

SIGN-SUPPORT.

1,109,921.

Specification of Letters Patent. Patented Sept. 8, 1914.

Application filed November 5, 1907. Serial No. 400,889.

To all whom it may concern:

Be it known that I, ERNEST A. HAVENS, a citizen of the United States, residing at Peoria, in the county of Peoria and State of Illinois, have invented certain new and useful Improvements in Sign-Supports; and I do hereby declare that the following is a full, clear, and exact description of the invention, which will enable others skilled in the art to which it appertains to make and use the same.

This invention has reference to car sign supports, and while applicable to all city or local traction cars, is particularly well adapted for supporting signs on the tops of interurban cars, where the signs are usually of considerable length, and where there is need for a desirable support for sustaining one or more signs which may be placed adjacent to each other or end to end.

One of the objects of the present invention, is a car sign support, capable of detachably sustaining on the tops of cars suitable signs, without the necessity of removing any of the support, or attaching said signs to removable parts of said support.

A further object of the present invention is a car sign support which is capable of being attached to the tops of different traction cars, regardless of the slope of the first deck or the difference in height from the top of the lower deck to the top of the upper deck.

Figure 1 represents in elevation a portion of a car, with my improvements in car sign supports attached thereto and supporting a sign-board thereon; Fig. 2 is a perspective of a standard adapted to be attached to the top deck of a car, to which is adjustably connected a slidable extension of said standard, which has pivotally connected thereto, a weighted arm; Fig. 3 is a reduced rear elevation of the slidable extension of the standard; Fig. 4 is an edge elevation of Fig. 3; Fig. 5 is a reduced front elevation of the main body of the standard; Fig. 6 is a side elevation of Fig. 5, partly in section; Fig. 7 is a perspective of a cleat adapted to be attached to the top deck of a car for holding a sign-board against endwise movement; Fig. 8 is a plan of the cleat seen in Fig. 7; Fig. 9 is an edge view of a cleat adapted to be attached to the lower deck of a car, for hold-

ing the lower edge of a sign-board from slipping, and Fig. 10 is a perspective of the cleat seen in Fig. 9.

Like numerals of reference indicate corresponding parts throughout the figures.

The car or portion thereof shown in Fig. 1, for convenience is referred to as A, having the top or roof consisting of the lower beveled deck B, which is correspondingly similar on both sides of the center of the car, and the central upper or top deck C, raised somewhat above the deck B. The bevel of the deck B varies in different cars, and it is very often found that the height between lower and upper decks B and C will vary considerably, so that not only must the support for the sign be capable of being attached to cars where the slope or bevel of the lower deck B varies, but also where the height between lower and upper decks B and C vary.

My improved sign support contemplates cleats for the lower and upper decks, the former to retain the lower edge of the signs in proper position and against slipping on said deck, while the latter will prevent endwise movement of said signs. Also a standard or suitable device attached to the upper deck by means of which a sign is held, preferably, central of its upper edge, and also by means of which a sign is readily attached to or detached from a car roof and from the cleats above referred to.

The standard referred to, is indicated as 1, of suitable height, with feet 2 by means of which the same may be suitably secured to the upper deck C, said feet 2 being beveled or inclined, as shown in Fig. 6, to conform somewhat to the slope of the deck B, whereby the body of said standard will assume normally a vertical position its front face being grooved or provided with a channel 3 and perforations 4. Slidably connected with the standard 1 is a slidable extension 5, of suitable length, which is provided with ribs 6 movable in the groove or channel 3, aforesaid, to retain the slidable extension 5 in proper position when extended on the standard 1, and the body of said extension 5 is slotted lengthwise as at 7, to provide for the proper adjustment of said extension, and by means of a bolt 8 which may be passed through either of the perforations 4

in the standard 1, and through the slot 7 of the extension, together with a nut, not shown, to engage with a threaded end of the bolt 8, the extension may be secured after being adjusted on the standard 1. To the upper end of the extension 5 is pivotally connected at 9, a weighted arm 10, provided with a finger portion 11, which normally stands in a vertical position in front of the upper end of the extension 5, and spaced a short distance from a rib 12 formed on the upper front face of the extension 5, as shown.

13 indicates a cleat, one or more of which may be used, which is adapted to be secured to the lower deck B of the car, in proximity to the wall supporting the upper deck C, and said cleat is provided with a pair of lugs 14 which converge toward each other at their upper ends, which are suitably spaced apart, forming an opening 15 between them, the matching faces of which are oppositely beveled as shown at 16. It is preferable, where the signs are of considerable length, to use at least three of such cleats, one to be placed at or near each end of the sign and one central thereof as shown in Fig. 1. Converging the lugs 14 toward each other at their upper ends and beveling their matching faces, as shown at 16, provides for the interchange or attachment of said cleats to different builds of cars, especially should the slope or bevel of the lower deck B, vary to any great extent. Fig. 9 illustrates this idea very clearly. If the slope of the deck B is normal, the sign will assume a vertical position between the lugs 14, but should the slope vary to any great extent, the cleats will still serve their purpose because the sign will enter between the lugs 14, somewhat in the manner shown in dotted lines in Fig. 9. The figure further showing that the cleats are not only adapted to different slopes of car decks, but may be also used on either side of the car, as the angle at which the signs may enter between the lugs 14 may be at great extremes.

The cleats which have been referred to as attached to the upper deck C for holding a sign against endwise movement, are indicated as 17, and comprise a plate 18 which may be, by means of screws or other suitable means, secured to the deck C, and which have a web 19 projecting centrally therefrom, to which is connected fingers 20 which project laterally therefrom and in opposite directions from each other, to provide the slotted openings 21 on opposite sides of the web 19, for purposes which will be described.

Assuming that the standard 1 and cleats 14 and 17 have been attached or secured to the decks B and C of a car, as shown in Fig. 1, and spaced so as to receive and sustain a predetermined size of car sign, to

attach a sign, such as the card or board D, on which may be suitable advertising matter, the weighted arm is first drawn up into the position as shown in full lines in Fig. 2 and in dotted lines in Fig. 3, when said sign with its opposite side edges are passed down through slotted openings 21 of each of the cleats 17 and the lower edge of the sign inserted between the lugs 14 of the cleats 13, when the weighted arm is dropped into the position shown in Fig. 1, causing the finger 11 thereof, to override the upper central edge of the sign, and retain that portion of the sign between the finger 11 and the lug 12 attached to or formed integral with the slidable extension 5 of the standard 1. The sign thus secured, is prevented from endwise movement by the webs 19 of the cleats 17, the lower edge is retained between the lugs 14 of the cleats 13, and the central upper portion of said sign is retained in manner described, between the finger 11 of the weighted arm, and the lug 12 of the slidable extension 5 of the standard 1. To detach the sign, the swinging arm 10 is again thrown up into the position shown in Fig. 2, when the sign may be lifted, and detached from the cleats 13 and 17.

The rear face of the weighted arm 10 is provided with an offset 10', see Figs. 2 and 3, which, when the weighted arm is swung up into the position shown in dotted lines in Fig. 3, will engage with an offset 5' which is formed on the upper end of the slidable extension 5, by the construction of the lug 12, formed thereon, and thereby limits the upward movement of said arm, and such engagement of offsets 10' and 5' for such parts have a cam relation to form a lock and thus the swinging arm may be temporarily retained in its elevated position until after the sign is placed, when it may be lowered for locking the sign in the manner stated.

In the event of an advertiser having a uniform size of sign and he desires the same displayed on cars of different traction lines, and the height of the upper and lower decks should vary, it is readily seen that the extension 5 of the standard 1 may be adjusted to accommodate the standard to such variations, by releasing the bolt and sliding the extension 5 on the standard 1, which will allow for the placing of the upper end of the slidable extension 5 so that the top edge of the sign may be placed between the lug 12 of said extension and the finger of the weighted arm 10. The provision of the slot 7 and slidable extension 5 and the perforations 4 in the standard 1, provides for extending the extension substantially the full length of the standard 1. And as stated, if the slope of the lower deck B varies on the different traction lines, 130

the peculiar construction of the cleat 13 will accommodate such cleats to the different cars.

It may be that it would be advisable to attach signs to the decks of cars where the ends of the signs would be adjacent or in proximity to each other, and if this is done, one cleat 17 will serve to hold the matching edges of the adjacent signs, and by the provision of the slotted openings 21 in said cleats, the meeting edges of adjacent signs may be slipped into opposite openings 21 of such cleats.

Having thus fully described my invention, what I claim and desire to secure by Letters Patent of the United States, is—

1. In combination in a sign support, a standard, a member slidably connected with said standard, means for securing said member in adjusted positions, and a weighted arm pivotally connected with said member to swing in a plane parallel to the face of the standard and having means to retain a sign when the weighted arm is in its lower position.

2. In combination in a sign support, a standard, a member slidably mounted on said standard, means for locking the member in adjusted positions on said standard, a weighted arm pivotally connected with said member to swing in a plane parallel to the face of the standard, said weighted arm being formed with a curved or elbow portion having a finger extending therefrom in a direction substantially parallel with the weighted arm, which finger is adapted to lock a sign between itself and said member when the weighted arm is at its lower position.

3. In combination in a sign support, a standard, a member slidably mounted on said standard, means for locking said member in adjusted positions on said standard, a rib formed on the upper portion of said member, which rib forms an offset on the upper end of said member, a weighted arm pivoted to said member, said weighted arm having a finger and also being provided with an offset which is adapted to engage said

first mentioned offset when the weighted arm is in its upper position to limit its upward movement, said finger being constructed so as to assume a downwardly extending position spaced from said rib when the weighted arm is lowered.

55

4. A car sign support, comprising a plurality of cleats to be attached to the lower deck of a car for receiving the lower edges of signs, cleats adapted to be attached to the upper deck of a car for receiving the side edges of adjacent signs to prevent endwise movement, and a standard adapted to be supported by the upper deck of a car and means connected with the said standard for detachably securing the upper edge of said signs.

5. A car sign support, comprising a plurality of members for receiving the lower edge of a sign, means with which the opposite edges of the sign may have a slidable relation and for preventing endwise movement of said sign, a standard, a member having a slidable relation with said standard, and an arm pivotally connected with said member, and provided with a finger for securing the upper edge of the sign between said finger and said member.

75

6. A car sign support, comprising a plurality of members to be secured to the lower deck of a car, with which the lower edge of a sign may have a detachable relation, cleats to be secured to the upper deck of the car and projecting laterally therefrom, said cleats provided with slotted portions with which the edges of said sign may have a slid- 80 able relation and be prevented from endwise movement, a standard supported by the upper deck, and an oscillatory member for securing the upper edge of said sign, said member having an adjustable relation with 85 said standard.

In testimony whereof I affix my signature, in presence of two witnesses.
